(57) **CLAIM**

The ornamental design for a tool accessory, as shown and described.

DESCRIPTION

Cross reference is made to copending U.S. design patent application Ser. No. 29/747,811 entitled "Tool Accessory" by Milan Bozic, which was filed on even date herewith; to copending U.S. design patent application Ser. No. 29/747,813 entitled "Tool Accessory" by Milan Bozic, which was filed on even date herewith, and to copending U.S. design patent application Ser. No. 29/747,814 entitled "Tool Accessory" by Milan Bozic, which was filed on even date herewith.

FIG. 1 is a perspective view of a tool accessory showing my new design;

FIG. 2 is a left side elevational view of the tool accessory of FIG. 1;

FIG. 3 is a right side elevational view of the tool accessory of FIG. 1;

FIG. 4 is a top plan view of the tool accessory of FIG. 1; FIG. 5 is a bottom plan view of the tool accessory of FIG. 1;

FIG. 6 is a front side elevational view of the tool accessory of FIG. 1; and,

FIG. 7 is a rear side elevational view of the tool accessory of FIG. 1.

The broken lines shown in the drawings illustrate portions of the tool accessory that form no part of the claimed design.

1 Claim, 7 Drawing Sheets
